(57) **CLAIM**

I claim the ornamental design for a chair, as shown and described.

DESCRIPTION

FIG. 1 is an upper perspective view of the chair showing my design.

FIG. 2 is a front view thereof;

FIG. 3 is a back view thereof;

FIG. 4 is a top plan view thereof;

FIG. 5 is a bottom view thereof;

FIG. 6 is a side view thereof;

FIG. 7 is an opposite side view thereof; and,

FIG. 8 is a partial close-up side view of a connection between front and back frames of the chair shown in FIG. 7.
